UNITED STATES PATENT OFFICE.

RAY SCOTT KITCHINGMAN, OF RACINE, WISCONSIN.

WARDROBE HANGER.

1,417,921.

Specification of Letters Patent. Patented May 30, 1922.

Application filed December 27, 1921. Serial No. 525,008.

To all whom it may concern:

Be it known that I, RAY SCOTT KITCHINGMAN, a citizen of the United States, and resident of Racine, in the county of Racine 5 and State of Wisconsin, have invented certain new and useful Improvements in Wardrobe Hangers; and I do hereby declare that the following is a full, clear, and exact description thereof.

10 The invention relates to a hanger for clothes and more especially to a construction desirable for wardrobe trunks.

Hitherto, coat hangers have been provided for wardrobe trunks rigid with a 15 spacer bar or support. Hangers have also been provided for one-piece dresses. These are sometimes termed "Princess" hangers.

The invention contemplates a structure wherein the advantages of the coat hanger 20 and the one-piece dress hanger are acquired at the same time. A structure is provided in which a one-piece dress hanger may readily be combined with, or detached from, a coat hanger.

25 Important features of the invention are the precise means by which the combination is attained. A socket member is rigidly attached to the coat hanger and downwardly projected therefrom. In one modification 30 a number of resilient arms cooperate with the socket member and have their ends received in apertures in the said member, whereby the one-piece dress hanger is supported.

35 Primary objects of the construction are the taking up of a minimum of room, the entire device being flat, and the elimination of danger of tearing garments, no projecting or catching corners resulting.

40 Other advantages are extreme simplicity of construction, ease of manufacture, and durability of parts. Other objects and advantages will appear as the description proceeds.

45 References had to the accompanying drawing in which Figure 1 is a side elevation of one modification of the invention. Figure 2 is a cross section thereof on the line 2—2.

50 Figure 3 is a side elevation of a modification, and

Figure 4 is a cross section on the line 4—4 of Figure 3.

A support 10 is provided with notches 11 55 to be received on rods in a wardrobe trunk and is integral with the coat hanger com-

prising outwardly directed arms 12. A socket member 13 has extensions 14 thereon with teeth 15 inwardly directed therefrom and embedded in the wood of the coat 60 hanger. The one-piece dress hanger is made of a single piece of wire bent into an arcuate portion 16, turned inwardly at the ends 17 and extending in directions substantially parallel to the arcuate portion 16 to points 65 18, where arms 19 are upwardly directed, extending through openings in a spacer 20. Fingers 21 are outwardly directed at the end of arms 19 and received in apertures in socket member 13. It is apparent that the 70 resilience of arms 19 facilitates the removal of the one-piece dress hanger from the coat hanger by the mere manual gripping of arms 19 at points above spacer 20. On the removal of the one-piece dress hanger, the coat 75 hanger may be utilized merely for the purpose of supporting a coat.

When, however, the two hangers are assembled in the position shown in Figure 1, they serve to support a one-piece dress, the 80 dress hanger supporting the upper part of the garment while the lower is folded over support 10, which may be placed on rods in a wardrobe trunk. It is apparent, therefore, that the flatness of the device is especially advantageous for wardrobe trunks 85 wherein one garment is packed closely upon another. Moreover, the entire construction is especially adapted to usage in wardrobe trunks as it obviates the need for carrying a 90 separate coat hanger and a separate one-piece dress hanger.

The modification shown in Figure 3 is of similar general outline, but the one-piece dress hanger 22 may be made of any desired 95 material, preferably wood, and is apertured to receive a pin 23 rigid with spring 24 mounted on pivot 25, directed inwardly through extension 14 on socket member 13. It is apparent that spring 24 may be grasped 100 by the fingers and pin 23, thereby retracted from the apertures in support 13 and one-piece dress hanger 22.

It is clear that the above modifications of the device are readily manipulable to attach or detach the coat hanger from the one-piece dress hanger, that a simple structure is provided made of a minimum number of parts and easy to manufacture.

Obviously, the invention may be embodied 110 in diverse structures and I do not desire to limit myself to the specific structures shown,

but wish to embrace a substantial range of equivalents within the scope of the appended claims.

I claim:—

- 5 1. The combination of a coat hanger, a one-piece dress hanger, a flat socket member having apertures therein downwardly directed from said coat hanger and having surfaces substantially continuous with the 10 surfaces of the coat hanger, and a pair of resilient members received within said socket member and having their ends projecting through said apertures, said resilient members supporting said one-piece dress hanger, 15 the sides of said socket member contacting with said resilient members throughout a considerable length thereof, to prevent lateral movement of said resilient members with respect to said socket member, said 20 resilient members being movable towards each other on the exertion of force thereon by the hand whereby said resilient members may readily be positioned in and secured to said socket members.
- 25 2. The combination of a support having a substantially straight upper surface, a coat hanger rigid therewith, a socket member, teeth on said socket member for making said socket member rigid with said coat hanger, said socket member having aper- 30

tures therein, a one-piece dress hanger, resilient arms upwardly extended therefrom, and a spacer member rigid with said arms, said resilient arms extending within said socket member and having ends outwardly directed through said apertures. 35

3. The combination of an elongated flat support having a recess in its lower edge at each end, a coat hanger integral therewith and having flat surfaces continuous with the 40 surfaces of the support, a flat socket member having tongues extending upwardly centrally of said coat hanger, teeth on said tongues securing said socket member to said coat hanger, the surfaces of said socket 45 member being substantially continuous with the surfaces of said coat hanger, said socket member having a pair of oppositely disposed openings therein, a one piece dress hanger, resilient arms extending upwardly therefrom, a spacer plate having openings receiving said arms, the ends of said arms being extended into said socket member, and laterally deflected through said apertures. 50

In testimony that I claim the foregoing 55 I have hereunto set my hand at Racine, in the county of Racine and State of Wisconsin.

RAY SCOTT KITCHINGMAN.
